YARN HANDLING APPARATUS

George R. Bethune, Jr., and Hoyt A. Green, Cartersville, Ga., assignors, by mesne assignments, to The Goodyear Tire & Rubber Company, a corporation of Ohio

Application June 2, 1953, Serial No. 359,092

3 Claims. (Cl. 57—53)

This invention relates to an apparatus for cabling yarn and more specifically to an improved system for handling yarn during mill operations.

In the manufacture of cable yarns and the like, a great amount of manual labor is required in handling the ply yarn spools and cable yarn spools between the various operations. Some of the manual operations not only are necessarily time consuming but also tedious and difficult to perform. By eliminating or reducing the severity of these operations, a substantial increase in efficiency of the mill operation can be effected with the resulting decrease in cost of the yarns themselves as well as reduction of maintenance cost.

In the usual textile mill operations, the ply yarns are wound on small spools during the ply twisting operation which are loaded into push trucks. The trucks then are carted to a spooler for winding larger spools of ply yarn from the smaller spools. After the larger spool is filled at the spooler, the spools are again stacked in a push truck for transportation to the twister where the larger spools are placed on the fixed creel of the cable twister. The ply yarns are threaded from the creel into the cable twister for the cabling operation. Usually each spool on the creel contains approximately the same amount of ply yarn so that all the spools are replaced at the same time. The empty or partially empty spools are removed from the creel and thrown in a push cart to be pushed back to the spooler for reloading. The cycle is then repeated. Obviously, considerable handling of the spools is required in this cycle of operations.

It is therefore an object of this invention to provide an apparatus that reduces the amount of handling required, thus increasing the efficiency of operations.

Another object of the invention is to provide a system that is flexible in that the various operations may be carried on independently with temporary storage areas available for the spools until needed.

A particular object of this invention is to provide an apparatus that reduces maintenance and replacement costs.

A still further object is to provide a comparatively inexpensive and easily installed system.

Other objects and advantages of this invention will become apparent hereinafter as the description thereof proceeds, the novel features, arrangements and combinations being clearly pointed out in the specification as well as the claims appended.

In the drawings:

Fig. 1 is a front elevation of a portion of a cable twister;

Fig. 2 is a partial end elevation of Fig. 1;

Fig. 3 is a schematic front elevation of a cable twister;

Fig. 4 is an end elevation of a spooler; and

Fig. 5 is a schematic layout of a typical installation of the invention.

In Figs. 1 and 2 the reference numeral 1 refers generally to the well-known cable twister or doubler twister apparatus having two banks of twisting units disposed in back-to-back relationship. In place of the usual stationary

2

creel mounted above the cable twister, the spools of ply yarn 4 are supported as illustrated upon the portable creel 5 suspended above the cable twister by pivotally mounted rollers 6, preferably centered over the twister 5 apparatus so as to serve as the supply creel for both banks of the double twister. The creel in its entirety comprises several sections positioned over the twister and connected together, for example by hook 8 registering in an opening on the bracket 9 of the adjacent section of the creel. The sections of the creel are more maneuverable and adaptable to be used with apparatus which are of various lengths so as to require a different number of spindles to supply the particular apparatus.

As best seen in Fig. 2, the ply yarns for each position on the cable twister are fed from the supply spools 4 supported on the spindles 11 mounted on the creel 5. As illustrated, the creel sections contain two banks of spindles but the number of banks of spindles provided will depend upon the maximum number of ply yarns required for any cable that may be twisted on the machine. The number of spindles in each bank corresponds generally to the number of spools on the double twister. The ply yarns from the spools on the creel are fed through the twister delivery rolls 12, 13 and 14 and the pigtail guide 15 which gathers the ply yarns together before passing through the traveler 16 mounted on the ring 17 of the ring rail 18 where they are cabled and collected on the spool as a twisted cord. It is to be understood that Fig. 2 illustrates the operation of one bank of twisting units 30 of the cable twister and the operation of the opposite bank is similar.

As illustrated in Fig. 3, three sections are joined together to form the creel for supporting the spools of ply yarn for the particular cable twister illustrated. The number of sections required may be varied according to the number of twisting units or stations on the twister. The sections are moved into the position over the cable twister either individually or as a unit and it has been found that it is not necessary to lock the creel sections in position on the monorail unless desired. Preferably the monorail is suspended, although it may be supported from the floor if desired, or any other type of conveying apparatus, such as a system of rails on the floor over which the creel sections move, may be used if desired.

In order to load and unload the spindles of the creel sections, it is desirable to provide a loading station apart from the cable twisters. If the particular mill operation requires a respooling operation, then this operation provides a very convenient and accessible position for loading the creel sections preparatory to the cabling operation. Alternately, separate portions of the way may be suitably adapted to position the creel sections while being loaded and unloaded.

For the purposes of illustration in Fig. 4 the numeral 10 represents a spooler of conventional construction wherein small spools 19 of ply yarn are rewound on large spools 20. The large spools of ply yarn 20 are placed then on the empty spindles of the creel sections supported on the monorail over the spooler apparatus. When the large spools 20 are in place on the spindles of the creel section above the spooler, the loaded creel section is then moved over the monorail to a storage section of track or in position over a cable twister. The empty large spools 20 upon which the smaller spools are rewound remain on the spindles of the creel section after the cabling operation, from which position the creel sections are removed to the storage section or to position adjacent the spoolers. The empty or partially empty spools are then removed from the spindles as needed and placed in position on the spooler for rewinding and when full are replaced on the spindles of the creel section. The large

spools usually remain on the spindles of the creel except when they are being rewound on the spooler.

In Fig. 5 a typical layout of the apparatus previously described is schematically illustrated in which the spoolers are represented by the letter S and the cable twisters by the letter T. The monorail track 7 is represented by a broken line with substantial sections of track available for storage of the creel sections and indicated by the letters ST. The storage section is spaced from the twisters or spoolers and shown as a convenient place to store the creel sections which temporarily are not required at either the spoolers or the twisters. The monorail track as illustrated is positioned centrally above each twister and spooler so that each side of the creel sections is in a position to supply the opposed banks of heads of the machines. Switches are provided to permit the creel sections to be moved selectively over the monorail system from any position to any other position with a minimum amount of manipulation of the track system.

In the operation of the apparatus, the creel sections are positioned on the monorail over one of the spoolers S. As the large spools of ply yarn are filled by the spooling operation, they are placed on the spindles of the creel. When a filled spool of yarn is in place on all spindles of the creel section, the section is moved over the monorail to the storage section ST or positioned over a cable twister T if needed. In the cable twisting operation, the requisite number of creel sections are positioned over twister and the sections connected together to form the creel and prevent any of the creel sections from creeping during the cabling operation. The ply yarns are fed into the cabling units from the creel for operation of the apparatus in the usual manner. When the spools are emptied or substantially emptied of ply yarn, the creel sections are moved over monorail to the storage section until needed or directly to the spoolers for reloading of the spools and creel sections with full spools of ply yarn to replace the removed sections over the cable twister.

While certain representative embodiments and details have been shown for the purpose of illustrating the invention, it will be apparent to those skilled in the art that various changes and modifications may be made therein without departing from the spirit or scope of the invention.

Having thus fully described our invention, what we claim and desire to secure by Letters Patent of the United States is:

1. In an apparatus for cabling yarn, the combination of a cable twister, a creel, a way and a loading station; said cable twister having a plurality of twisting units thereon for cabling ply yarn; said creel having at least two sections, each section comprising a framework, a plurality of spindles mounted on said framework and adapted to rotatably support yarn-carrying spools of ply yarn thereon, mounting means on the framework to engage said way for movement of the creel along said way, and means to link at least two sections together for simultaneous movement of said sections along said way, said sections cooperating to form said creel to supply ply yarns to all of said twisting units of said cable twister; said way extending between said cable twister and loading station to define a path over which said creel may be moved, a first portion of the way adjacent said cable twister where the ply yarns are fed directly from the spools on said creel into the twisting units of the cable twister, a second

portion of the way removed from said cable twister whereon said creel may be stored until needed, and a third portion of said way adjacent said loading station whereon said creel may be located for the placing of filled spools of ply yarn on the spindles of said creel; and said loading station including means for supplying filled spools of yarn for loading said creel.

2. In an apparatus for cabling yarn, the combination of a cable twister, a creel, a way and a loading station; said cable twister having a plurality of twisting units thereon for cabling ply yarn; said creel having at least two sections, each section comprising a framework, a plurality of spindles mounted on said framework and adapted to rotatably support yarn-carrying spools of ply yarn thereon, mounting means on the framework to engage said way for movement of the creel along said way, and means to link at least two sections together for simultaneous movement of said sections along said way, said sections cooperating to form said creel to supply ply yarns to all of said twisting units of said cable twister; said way comprising a mono-rail extending between said cable twister and loading station to define a path over which said creel may be moved, a first portion of the monorail mounted over said cable twister where the ply yarns are fed directly from the spools on said creel into the twisting units of the cable twister, a second portion of the mono-rail removed from said cable twister whereon said creel may be stored until needed, and a third portion of said mono-rail adjacent said loading station whereon said creel may be located for the placing of filled spools of ply yarn on the spindles of said creel; and said loading station including a spooler having a plurality of spooling units thereon for filling spools with ply yarn from which units the filled spools are transferred to the spindles on said creel positioned adjacent said loading station on said way.

3. In a system of cabling yarn, a cable twister having a plurality of twisting units, a plurality of spools of ply yarn supported on a creel, said creel having at least two sections, each section comprising a framework and a bank of substantially parallel spindles adapted to rotatably support a plurality of spools thereon, said creel sections cooperating to supply yarns to all of said twisting units on said cable twister; means to move said creel into operative position adjacent said cable twister, said means comprising a way providing a predetermined path of movement for said creel, a first portion of said way being adjacent said twister where the ply yarn is fed directly into the said twisting units of said cable twister from said creel when positioned on this portion of the way, the creel being mounted for movement along said way; a loading position adjacent a second portion of the way away from said twister; and a storage section on a third portion of said way to provide means for storing the creel sections until needed.
